UNITED STATES PATENT OFFICE.

WILLIAM B. HORN AND CLIFFORD H. GIBBONS, OF JACKSON, CALIFORNIA.

CLAY OR GRAVEL WASHING MACHINE.

SPECIFICATION forming part of Letters Patent No. 636,995, dated November 14, 1899.

Application filed February 6, 1899. Serial No. 704,733. (No model.)

To all whom it may concern:

Be it known that we, WILLIAM B. HORN and CLIFFORD H. GIBBONS, citizens of the United States, residing at Jackson, county 5 of Amador, State of California, have invented an Improvement in Clay and Gravel Washing Machines; and we hereby declare the following to be a full, clear, and exact description of the same.

10 Our invention relates to an apparatus which is especially designed for washing clay or gravel which contains valuable or precious metals and separating the latter from the clay or gravel.

15 It consists in the parts and the constructions and combinations of parts hereinafter described and claimed.

Referring to the accompanying drawings, Figure 1 is a side elevation of the machine. 20 Fig. 2 is a lateral section on line xx of Fig. 1. Fig. 3 is a detail in perspective of one end of the cylinder, showing the retaining-flange c' .

A is a frame of any suitable or desired construction, and B is a trough having the general shape of half a cylinder and properly supported in the frame. At one end this cylindrical trough is contracted toward its axis, as shown at E' , in the manner of half of a bottle-neck. Within this trough is journaled 25 a cylinder C, which is made of longitudinal iron bars riveted at intervals to circular rims the hubs of which are fixed to a central longitudinal shaft, as shown. The periphery of the cylinder coincides closely in shape with the interior of the trough B, but is nearer to the bottom than to the sides. The bars c composing the cylinder are approximately one and one-half inches wide by half an inch thick, with interspaces one-eighth of an inch 30 wide. Interspaced between the flat bars are six or more, made of angle-iron, with the angle-flanges projecting inwardly. One end of the cylinder is open, as shown, to receive the material which is to be operated upon by it, 35 with a three-inch interior flange c' to prevent the material from washing into the trough. The other end is contracted, as shown at C' , and has an extension or neck C^2 , resembling the neck of a bottle. These circular rims of 40 the cylinder have radial arms D extending to the hubs, and these, as previously stated, are fixed to a central shaft E , upon which the cyl-

inder is mounted. This shaft is properly journaled in the framework and may be driven by crank, pulley, or other device, as indicated 55 at F. The cylinder and trough are set at a slight angle, declining from the larger end toward the discharge. In the lower part of the trough is a depression or chamber G, which serves to catch and retain any gold or 60 heavy metal which arrives at that point. This chamber is in the form of a channel cut transversely through the bottom of the trough and is closed by a door fitting closely against gaskets and secured by screw-bolts, latch, or 65 other suitable device. The interior of the cylinder C is provided with inwardly-projecting teeth or ribs H, by which the material is agitated and broken up as the cylinder is 70 revolved.

The operation of the apparatus will be as follows: The clay or gravel to be treated is delivered into the larger and higher end of the cylinder and water is delivered into the trough, rising into the cylinder and mixing 75 with the material which has been delivered therein. The cylinder is rotated and the material is constantly acted upon by the inwardly-projecting teeth or ribs and is thus thoroughly disintegrated, the action being especially favorable in the case of material 80 which contains adhesive clay, the latter being broken up and separated so that fine gold which may be mixed therewith will be eventually separated from the clay and passing 85 through the sides of the cylinder into the trough will be eventually concentrated and arrested in the depression G.

The inclined or tapering construction of the neck C' of the bottle-shaped cylinder tends to 90 prevent the clay or gravel from passing out of the cylinder before it has been entirely disintegrated and gives the heavier parts a chance to settle at this point, while the lighter material will gradually flow out through the 95 small bottle-shaped neck and be discharged. The inclined portion C of the neck is made, without openings, of sheet metal, the cylindrical portion of the neck being made with interspaced bars similar to the main body C. 100

Having thus described our invention, what we claim as new, and desire to secure by Letters Patent, is—

1. A device for separating gold from clay

or gravel consisting of an inclined cylinder composed of longitudinal interspaced bars, said cylinder having one end made conical and of imperforate material, and a neck prolongation of said conical end formed of parallel interspaced bars serving as a final screen for any material which passes over the said imperforate portion, an inclined segmental trough having an end and an extension there-
10 of conforming to the cylinder and its imperforate conical end and neck extension, said trough having a transversely curved and gated depression at or near the junction of the imperforate section with the main body of the
15 screen.

2. A device for separating gold from clay or gravel consisting of an inclined cylinder having one end open and the opposite end made conical and provided with an extension
20 of reduced diameter, said cylinder and said extension formed of longitudinal interspaced

bars connecting the one with the other by means of a conical imperforate section whereby the reduced portion of the cylinder serves to separate the material which passes over the intermediate imperforate surface to the final discharge, a retaining-flange c' at one end of the cylinder, means whereby the cylinder is rotated, a semicircular trough adapted to contain water and conforming to the cylinder and the reduced extension and conical portion thereof, and a well or chamber in said trough proximate to the conical end of the cylinder and provided with a gate-controlled outlet.

In witness whereof we have hereunto set 35
our hands.

WILLIAM B. HORN.
CLIFFORD H. GIBBONS.
